UNITED STATES PATENT OFFICE.

JOHN CECIL DAVIDSON, OF PAHIATUA, NEW ZEALAND.

SCRAPER DEVICE FOR CLEANING FLOORS AND OTHER SURFACES.

Application filed September 27, 1921. Serial No. 503,665.

To all whom it may concern:

Be it known that I, JOHN CECIL DAVIDSON, subject of the King of Great Britain, residing at Pahiatua, in the Dominion of New Zealand, have invented new and useful Improved Scraper Devices for Cleaning Floors and Other Surfaces, of which the following is a specification.

This invention relates to a device that has been designed for use in cleaning surfaces such as the floors of milking sheds, barns, stables, stores and the like, where accumulations of manure and dirt of various kinds are likely to result.

The appliance designed for this purpose is adapted to be pushed across the surface of the floor and to gather in front of it the débris accumulated thereon, and its construction is such that it may be provided with different forms of scraping edges so as to adapt it to any particular purpose. It is also so constructed that the scraping edges may be tilted up from the floor level when the appliance is to be drawn rearwards, thus allowing for it being used with a to and fro motion and for it running idly on the rearward motion.

The device is formed by a pair of vertically disposed metal plates arranged to diverge from one another in broad V form and having a handle projecting rearwards from their point of connection. The lower edges of these plates form the scraping edges and for this purpose may be provided with renewable wearing strips of approved nature. The device, especially in its heavier forms, may have combined therewith small rollers or wheels mounted behind the plates and so disposed that when the device is tilted by levering the handle downward, the weight will rest on these rollers or wheels so that it may be drawn rearwards while its scraping edges are clear of the surface being cleaned.

The invention is illustrated in the accompanying drawings, in which:—

Figure 1 is a plan, and

Figure 2 a side elevation thereof.

According hereto two metal plates A—A of approved width and thickness and of equal length, are arranged in vertical planes and to diverge outwardly and forwardly from one another to form the broad V shape shewn. The spread of these plates may be of any desired width according to the purposes for which the appliance is to be used

and the width of surface to be operated on at each operation thereof. The plates are secured together by any approved means or method. In the drawing they are shewn as being bolted together through flanges B—B arranged face to face and forming continuations of the plates. These flanges are also shewn as being shaped with bends C extending longitudinally in them and curving upwards and rearwards so that when the flanges are placed together a socket is formed by the two bends in which the handle D for operating the appliance is secured. The handle thus extends rearward and upwards at the proper incline to facilitate the working of the scraper. Any other approved manner of forming or attaching a handle socket at the rear of the jointing angle of the plates may, however, be adopted.

Each plate may also be formed with one or more corrugations E made longitudinally in its length in order to strengthen it against bending.

Along the lower edge of each plate, on its forward face, a wearing strip F is secured so as to project below the bottom of the plate and to act as the scraping or cleaning edge. This strip may consist of metal plate, or brushes, or leather or rubber wipers, as may be desired, and may be made removable so that when worn, a fresh strip may be put in its place.

An appliance is thus produced that may be pushed across the floor or surface to be cleaned, the edges of the plates scraping such surface with a sliding action so as to remove any adhesive or loose dirt or other matter, which loosened matter then collects before the plates and is pushed along to any desired point. The weight of the appliance will ensure of the necessary frictional contact of the scraping edges with the surface being cleaned.

In order to facilitate the rearward travel of the appliance and to provide for it being worked to and fro over a surface in the same manner as that in which a lawn mower is worked, i. e., by moving idly on the rearward movement, a spindle G is arranged to extend transversely across the rear of the angle of junction of the plates and is carried in bearings G' fixed on the rear faces of such plates. On this spindle small wheels or rollers H are mounted so that they may rotate freely. These rollers are so adjusted in height that their peripheries just clear the

floor surface when the plates are on the level. They also serve as a pivot on which the appliance may be tilted upwards by depressing the handle, and will then carry the weight 5 of the appliance so that it may be drawn rearwards on such rollers.

Thus the appliance in its working may be placed flat on the surface and pushed forward, and then tilted on to its rollers and 10 drawn backwards with its edges raised clear of such surface.

I claim:—

1. A scraper cleaner for floors and other surfaces formed by a pair of vertically disposed metal plates connected end to end and arranged to extend forwardly and outwardly 15 from one another, a handle socket extending rearwardly from the angle of junction of such plates and a handle inserted in such 20 socket, substantially as specified.

2. In a scraper cleaner for floors and other surfaces constructed as described in claim 1, a renewable wearing strip fastened along the bottom edge of each plate and extending below such edge, substantially as 25 specified.

3. A scraper cleaner for floors and other surfaces comprised by a pair of vertically disposed metal plates connected end to end and diverging outwardly and forwardly 30 from one another, a handle socket extending rearwards from the angle of junction of the plates, a handle inserted in such socket, and wheels or rollers journalled on a spindle extending across the rear end of such plates 35 and beneath the handle socket, substantially as specified.

In testimony whereof, I affix my signature.

JOHN CECIL DAVIDSON.
